Patented Aug. 24, 1976

241,180

ELECTRIC RAZOR

Klaus Limberg, Solingen, Germany, assignor to
Robert Krups, Solingen, Germany

Filed Mar. 14, 1974, Ser. No. 451,372

Claims priority, application Germany Sept. 27, 1973

Term of patent 14 years

Int. Cl. D28—03

U.S. Cl. D95—3 A

FIG. 1 is a perspective view of an electric razor showing my new design;

FIG. 2 is a front elevational view thereof;

FIG. 3 is a rear elevational view thereof;

FIG. 4 is a left side elevational view thereof;

FIG. 5 is a right side elevational view from the opposite side; and

FIG. 6 is a bottom plan view thereof.

I claim:

The ornamental design for an electric razor, substantially as shown.
